UNITED STATES PATENT OFFICE.

GUSTAF EMIL HESSE, OF BROOKLYN, NEW YORK, ASSIGNOR OF ONE-HALF TO GEORGE H. ROBINSON, OF NEW YORK, N. Y.

TORPEDO.

1,302,162.

Specification of Letters Patent. Patented Apr. 29, 1919.

Application filed June 5, 1917. Serial No. 172,878.

To all whom it may concern:

Be it known, that I, GUSTAF EMIL HESSE, a subject of the King of Sweden, and a resident of Brooklyn, in the county of Kings and State of New York, have invented certain new and useful Improvements in Torpedoes, of which the following is a specification.

The invention relates to torpedoes of a character to be discharged from a gun or torpedo tube at an object to be destroyed.

My invention involves a new construction of torpedo, whereby the torpedo when discharged may be held firmly in its course and have a straight and dependable trajectory.

In accordance with my invention the torpedo has rigidly secured to it a propeller and the forward motion or travel of the torpedo under or due to the action of the propeller is inaugurated and maintained by the rotation of the torpedo as a whole on its longitudinal axis. The torpedo is maintained in rotation during the period or distance it is desired the same shall travel, by the action of a gas generated therein and escaping under pressure through reversely arranged passages extending through opposite side walls of a portion of the torpedo from an interior gas-chamber to the exterior of the torpedo. The power gas or gas for rotating the torpedo is produced by the automatic ignition of a suitable charge of powder or the like within a confined gas-chamber at the interior of the torpedo immediately on the discharge of the torpedo from a gun or tube, this charge of gas-producing powder being entirely independent of the usual explosive charge at the forward end of the torpedo. The ignition of the gas-producing charge is effected on the discharge of the torpedo from a gun or tube by the action of an inner firing pin striking a fulminate suitably positioned with relation to said charge, and the gas resulting from the ignition of said charge is relied upon, on its escape through the aforesaid reversely disposed passages, to effect the rotation of the torpedo and its propeller and consequently the forward movement of the torpedo toward the object aimed at. The power gas is confined within a chamber whose only outlets are the aforesaid reversely disposed passages, and to insure economy in the use of the gas and regularity in the movement of the torpedo, I provide within the gas-chamber automatic

slide valves or gates which on the first generation of the gas, more or less close the entrances to said passages (the gas then being under maximum pressure), and then gradually recede from said entrances as the gas-pressure lessens and it is desirable to permit a gradually increased volume of the gas to enter said passages.

The invention will be fully understood from the detailed description hereinafter presented, reference being had to the accompanying drawings, in which:

Figure 1 is a longitudinal section through a torpedo embodying the features of my invention;

Fig. 2 is a corresponding section on a larger scale through a portion of the same;

Fig. 3 is a vertical transverse section, on a still larger scale, through the same, taken on the dotted line 3—3 of Fig. 2;

Fig. 4 is a corresponding section through a portion of the same, taken on the dotted line 4—4 of Fig. 2, and

Fig. 5 is a detached vertical transverse section through a detail of the same.

In the drawings, 10 designates the torpedo as a whole, and this torpedo comprises a rearwardly tapered casing-shell 11, a forward casing-shell 12 of the usual type, and an intermediate shell or casing 13, these several shells being secured together and constituting the exterior casing of the torpedo. The shell 12 will contain the usual explosive charge 14 and be provided with the customary firing-pin 15. The rear end of the shell 11 has rigidly secured to it a propeller 16, and this propeller during the rotary motion of the torpedo impels the torpedo forwardly. The propeller derives its motion solely by the rotation of the torpedo as a whole.

The shells 11, 12 may be of any suitable or desired construction.

The shell 13 possesses the novel features of my invention, and this shell 13 is preferably of durable cast metal and of cylindrical outline and at its opposite ends said shell 13 has secured to it the adjoining ends of the shells 11, 12. The shell 13 has an integrally closed rear end, and at its forward end said shell is adapted to be closed by a plug 17 which may be screw-threaded and screwed into the end of the shell 13. A non-conducting layer 18 is applied between the forward end of the shell 13 and the explo-

sive charge 14. The shell 13 is formed in its opposite sides with reversely directed curved slots or passages 19, 20, these passages corresponding with each other, except that they 5 are reversed in direction. The passages 19, 20 are employed in connection with a gas generated within the chamber 21 of the casing 13 for impelling rotary motion of the torpedo. Within the rear end of the casing 10 or shell 13 is placed a charge of powder or equivalent substance 22, and within said end of the casing and within the charge of powder 22 is confined a tube 23 which is slotted at its rear end, as shown in Fig. 2, and at 15 its front end contains a reasonably heavy firing-pin 24 which is normally held stationary by a weak or fragile transverse pin 25 which extends through the firing-pin 24 and the opposite sides of the tube 23, as 20 shown in Fig. 5.

Within the rear slotted end of the tube 23 is placed a fulminate 26, the fulminate being in line with the pin 24, which is slightly pointed at its inner end.

25 Within the casing 13 are provided two gates or valves 27, 28 arranged to slide over and from the inner ends of the passages 19, 20 so as to more or less close said passages at the starting of the operation and then 30 recede gradually from over said passages, thereby gradually widening the entrances for the gas to said passages. The gates or valves 27, 28 may slide on the inner wall of the casing 13 and are held by the free ends 35 of bowed springs 29, 30 whose rear ends are rigidly secured to the casing or shell 13. When the springs 29, 30 are in their initial condition, shown in Fig. 2, they hold the valves or gates 27, 28 rearwardly away from 40 the entrances to the passages 19, 20, but when said springs are straightened out by pressure created within the chamber 21, they slide said valves or gates frontwardly over the entrances to the passages 19, 20, and then 45 as the pressure within the chamber 21 gradually lessens, the springs 29, 30 gradually return to their initial position and at the same time draw the valves or gates 27, 28 rearwardly from over the entrances to the 50 passages 19, 20. The springs 29, 30 have connected with them pins 31 which enter holes 32 in the sides of the casing or shell 13 and normally bear against reasonably yieldable plugs 33 (which may be of wax) located 55 within the outer portions of said holes. The springs 29, 30 normally engage a small bearing surface, as a ball 34 (Fig. 4), held by the heads of the pins 31, leaving said heads exposed to the pressure which may be 60 created within the chamber 21. The pins 31 have loops on their head portions which are freely strung upon the springs 29, 30. When the torpedo of my invention is discharged from a gun or tube, the inertia of 65 the firing-pin 24 causes the breaking of the

weak pin 25, and thereupon the pin 24 slides along the tube 23 and strikes the fulminate 26, this resulting in the ignition of the charge of powder 22 and the creation thereby of a large volume of gas within the confining chamber 21. This gas acts against the springs 29, 30 and pins 31, and the pins 31 are thereby forced outwardly, driving the plugs 33 from the holes 32, with the result that the springs 29, 30 are straightened 70 out and move the valves or gates 27, 28 to nearly close the entrances to the passages 19, 20. The gas created within the chamber 21 serves as the power, escaping through the reverse passages 19, 20 to rapidly rotate the 80 torpedo on its longitudinal axis. As the gas pressure lessens in the chamber 21 the springs 29, 30 gradually draw the gates or valves 27, 28 rearwardly from over the entrances to the passages 19, 20 so that as the 85 pressure of gas lessens the volume entering the passages 19, 20 may be increased and the torpedo kept in rotation. The purpose is to permit only enough of the gas in the chamber 21 to escape through the reverse passages 19, 20 to keep the torpedo in rotation, and the charge of powder 22 or other substance employed to create the gas will be sufficient, in quantity, to make enough gas to keep the torpedo in rotation during the 95 distance it is designed the torpedo shall travel before striking the object it was aimed at. During the rotation of the torpedo by the discharge of gas from the chamber 21 into and through the reverse passages 19, 20, the rigidly affixed propeller 16 effects the travel of the torpedo. The revolving motion of the torpedo acts to hold the torpedo firmly in its course, giving it a straight and dependable trajectory movement. When the main firing-pin 15 strikes the intended object, the material 14 is exploded in the customary way. My invention does not pertain to the forward end or part 100 of the torpedo, but resides more particularly, with a rigidly affixed propeller 16, to the features contained within the casing or shell 13, with the use of which the torpedo is caused to rapidly revolve.

I do not limit the invention to the particular details of mechanism contained within the chamber 21 since my invention is of broader scope than such details and involves not only a new construction of torpedo but a new method of propelling 110 the same, this method broadly comprising the rotation of the torpedo to inaugurate and maintain the forward travel of the same.

What I claim as my invention and desire to secure by Letters Patent, is:

1. A torpedo having a propeller and means for effecting the rotation of the torpedo on its projection from a gun or tube.
2. A torpedo having means for effecting 130

its rotation on its longitudinal axis on the projection of the torpedo from a gun or tube, and also having means operable from such rotation for effecting the forward travel of the torpedo.

3. A torpedo having means for effecting its rotation on its longitudinal axis on the projection of the torpedo from a gun or tube, and also having means operable from such rotation for effecting the forward travel of the torpedo, said means for effecting the rotation of the torpedo comprising a gas-producing charge therein, means for firing said charge on the projection of the 15 torpedo, and an exit for the gas in a direction to permit the gas to rotate the torpedo.

4. A torpedo having means for effecting its rotation on its longitudinal axis on the projection of the torpedo from a gun or tube, and also having means operable from such rotation for effecting the forward travel of the torpedo, said means for effecting the rotation of the torpedo comprising a gas-producing charge therein, means for firing said charge on the projection of the 25 torpedo and an exit for the gas in a direction to permit the gas to rotate the torpedo, and means for automatically controlling the flow of gas through said exit.

5. A torpedo having in its head an explosive charge and means for effecting the explosion of the same, at its rear portion a fixed propeller, in its body portion a gas-chamber having reversely disposed outlets 30 for gas to effect the rotation of the torpedo, and in said body portion a gas-producing charge, with means to explode it on the projection of the torpedo, the gas entering said chamber.

6. A torpedo having in its head an explosive charge and means for effecting the explosion of the same, at its rear portion a fixed propeller, in its body portion a gas-chamber having reversely disposed outlets 45 for gas to effect the rotation of the torpedo, in said body portion a gas-producing charge, with means to explode it on the projection of the torpedo, the gas entering said chamber, and means for automatically controlling the escape of the gas through 50 said outlets in accordance with its pressure.

7. A torpedo having in its head an explosive charge and means for effecting the explosion of the same, at its rear portion a fixed propeller, in its body portion a gas-chamber having reversely disposed outlets 55 for gas to effect the rotation of the torpedo, and in said body portion a gas-producing charge, with means to explode it on the projection of the torpedo, the gas entering said chamber, said means for exploding the gas-producing charge comprising a tube, a fulminate at the inner end thereof, and a firing-pin yieldingly held in the other end of 60 said tube.

8. A torpedo having in its head an explosive charge and means for effecting the explosion of the same, at its rear portion a fixed propeller, in its body portion a gas-chamber having reversely disposed outlets 70 for gas to effect the rotation of the torpedo, in said body portion a gas-producing charge, with means to explode it on the projection of the torpedo, the gas entering said chamber and means for automatically controlling the 75 escape of the gas through said outlets in accordance with its pressure and comprising bowed springs held at one end and having slide valves at their free ends adapted to move over said outlets when the springs are straightened out under the maximum gas pressure and to gradually recede from over 80 said outlets as the gas pressure lessens and said springs gradually become restored to their initial condition.

9. A torpedo having in its head an explosive charge and means for effecting the explosion of the same, at its rear portion a fixed propeller, in its body portion a gas-chamber having reversely disposed outlets 90 for gas to effect the rotation of the torpedo, in said body portion a gas-producing charge, with means to explode it on the projection of the torpedo, the gas entering said chamber, and means for automatically controlling the 95 escape of the gas through said outlets in accordance with its pressure and comprising bowed springs held at one end and having slide valves at their free ends adapted to move over said outlets when the springs are straightened out under the maximum gas pressure and to gradually recede from over 100 said outlets as the gas pressure lessens and said springs gradually become restored to their initial condition, pins engaged with 105 said springs and entering holes in the shell of the torpedo, and yieldable plugs in the outer ends of said holes to be driven out on the outward movement of said pins due to the gas-pressure.

10. A torpedo comprising a forward shell-section having an explosive charge and means for exploding the same, a rear shell-section having a propeller secured to it, and an intermediate shell-section affording a gas-chamber and containing a gas-producing 115 charge, with means to explode it on the projection of the torpedo, said intermediate shell-section having means to permit the escape of the gas in a direction to rotate the 120 torpedo on its longitudinal axis.

11. A torpedo comprising a forward shell-section having an explosive charge and means for exploding the same, a rear shell-section having a propeller secured to it, and an intermediate shell-section affording a gas-chamber and containing a gas-producing 125 charge, with means to explode it on the projection of the torpedo, said intermediate shell-section having means to permit the es- 130

cape of the gas in a direction to rotate the torpedo on its longitudinal axis, and also means for automatically controlling the escape of the gas in accordance with its pressure.

5 Signed at New York city, in the county

of New York and State of New York, this 4th day of June, A. D. 1917.

GUSTAF EMIL HESSE.
